IMPROVEMENT IN STEAM GENERATORS.

ROBERT BAILEY, OF IDAHO CITY, IDAHO.

Letters Patent No. 60,611, dated December 18, 1866.

The Schedule referred to in these Letters Patent and making part of the same.

TO ALL WHOM IT MAY CONCERN:

Be it known that I, ROBERT BAILEY, of Idaho City, in the county of Boise, and Territory of Idaho, have invented a new and useful Improvement in Steam Boilers; and I do hereby declare that the following is a full, clear, and exact description thereof, which will enable others skilled in the art to make and use the same, reference being had to the accompanying drawings, forming part of this specification, in which—

Figure 1 is a side elevation of the boiler.

Figure 2 is a vertical section of the boiler taken in the plane of the line $z z$, fig. 4.

Figure 3 is a horizontal section of the boiler taken in the plane of the line $y y$, fig. 1.

Figure 4 is a horizontal section of the boiler taken in the plane of the line $z z$, fig. 2.

Similar letters of reference indicate like parts.

This invention relates to improvements in a steam boiler, and consists in constructing it in sections in such manner that it may be readily opened and taken apart for repairing or cleaning the fire flues and spaces in the different sectional parts, which fire flue and spaces are so divided and arranged as to present an immense amount of fire surface in proportion to the size and weight of the boiler, compared with ordinary boilers. The boiler, as a whole, is very compact and strong, and although it may be advantageously used anywhere, it is particularly adapted to mining purposes in distant interior localities, where transportation is difficult and expensive, on account of its weight being comparatively small and the great portability it possesses by division into sections. My sectional boiler has two principal parts divided vertically, each principal part being also divided into two different sections.

In fig. 1, A A represent the two principal parts or sections, each of which is divided into two sections, B B', as shown clearly in fig. 2. The fire grate C extends under both principal sections, and between them is a vertical fire space D, over the fire chamber E, which leads directly into the exit flue F, at the top of the boiler. The central subdivisions or sections, B' B', on each side of the fire space D, have running through them a series of horizontal or nearly horizontal tubular fire flues a a a. The outside jackets or sections, B B', may be modified in their construction as represented in the drawings, wherein are shown two modes of arranging the flues and fire spaces; one of these sections being built with tubular fire flues running through water compartments, and the other with a flat fire space or flue between two flat water compartments, either of which methods of construction may be adapted in my sectional boiler. In figs. 2 3 4, b b b, are seen the tubular fire flues passing transversely through the water compartments c c, of one section, between which is also a larger fire space d; and in the other section is seen the flat fire flue e, between the water compartments f f. And between both sections B' B', are fire spaces e' e'. The two outer sections or jackets B B', are pivoted to the central sections B' B', through trunnions at their lower ends by rods g g which pass through the shells on each side of the boiler, allowing the jacket sections to be opened outward readily for the purpose of repairing and cleaning the scale and ashes in the fire flues and spaces when necessary, as shown by fig. 1, in red. The central sections B' B' may be made with water compartments i i, extending outside of the jacket sections and enclosing fire spaces j j between them, as shown in figs. 3 and 4. The grate bars c c are made hollow, with their ends opening into the central sections B' B', as shown in fig. 3, so that the water in the boiler shall circulate through them. At the upper end of the fire space D is a damper, k, opening into the exit flue F. This damper may be opened for direct draught when the fire is kindled, but for making steam it is closed, when the products of combustion will pass indirectly to the exit flue through all the fire flues and spaces, as indicated by the arrows, fig. 2, and thus act upon a very large extent of fire surface, and make steam very rapidly with a small consumption of fuel. The boiler may have doors m opening into the fire chamber on both sides; the feed pipes n n connect with each section of the boiler, and the steam pipes s s lead from each section to a common steam pipe connected with the steam cylinder of the engine. Gauge cocks t t are placed on all the sections of the boiler.

Having described my invention, what I claim as new, and desire to secure by Letters Patent, is—

1. I claim a sectional steam boiler divided into four principal parts, two central sections B' B', and two external jackets B B', constructed, combined, and arranged as herein described.

2. I claim the combination of the hollow grate bars with the central sections B' B', and the jackets B B', arranged and connected as herein described.

3: I claim the damper k, for giving direct or indirect draught through the boiler, in combination with the fire spaces D and e e', and the exit flue F, arranged and operating as and for the purposes herein described.

ROBERT BAILEY.
